US0D1050457S

(12) **United States Design Patent** (10) **Patent No.:** **US D1,050,457 S**
(45) **Date of Patent:** **** Nov. 5, 2024**

(54) **MASSAGER CONTROLLER**

(71) Applicant: **Shenzhen Asda Technology Co., LTD,**
Shenzhen (CN)

(72) Inventor: **Shupeng Li**, Shenzhen (CN)

(73) Assignee: **Shenzhen Asda Technology Co., LTD,**
Shenzhen (CN)

(**) Term: **15 Years**

(21) Appl. No.: **29/925,127**

(22) Filed: **Jan. 23, 2024**

(30) **Foreign Application Priority Data**

Jul. 25, 2023 (CN) 202330467793.8

(51) **LOC (14) Cl.** **24-01**

(52) **U.S. Cl.**

USPC **D24/200**; D13/168

(57) **CLAIM**

The ornamental design for a massager controller, as shown and described.

DESCRIPTION

FIG. 1 is a first perspective view of a massager controller showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the massager controller that form no part of the claimed design.

1 Claim, 8 Drawing Sheets
